UNITED STATES PATENT OFFICE.

HEINRICH SÜSSMANN, OF BERLIN, GERMANY, ASSIGNOR TO DEUTSCHE GASGLÜHLICHT AKTIENGESELLSCHAFT (AUERGESELLSCHAFT), OF BERLIN, GERMANY, A CORPORATION OF GERMANY.

INCANDESCENT GAS-BURNER.

1,024,462.

Specification of Letters Patent. Patented Apr. 23, 1912.

Application filed October 7, 1910. Serial No. 585,896.

To all whom it may concern:

Be it known that I, HEINRICH SÜSSMANN, engineer, a subject of the Emperor of Germany, residing at 8-12 Rotherstrasse, Berlin, in the German Empire, have invented certain new and useful Improvements in Incandescent Gas-Burners, of which the following is a specification.

Incandescent gas burners are already known in which the upper part of the burner carrying the gallery for the cylinder is fitted with a narrower burner head than that of a standard incandescent gas burner. In these known arrangements the upper part of the burner carrying the gallery, what is known as the crown of the burner, is, in well known manner slipped over the Bunsen tube, so that the heat coming from the flame, is, by conduction and radiation transmitted to the burner head and thence to the outer tubular part of the burner, the crown of the burner.

The object of the present invention is an arrangement for transforming the usual incandescent gas burner of standard size into what is known as a "Bijou" or "Gem" burner, that is to say a smaller burner. This transformation is effected as follows: Into the burner crown of a standard incandescent gas light a tube is slipped, after removal of the head ring and the parts in the burner head, which tube at the top is closed by a gauze plate and so far projects beyond the crown tube of the burner as to permit another mantle to be placed on.

With the new arrangement the additional advantage is obtained that the heat passing from the flame to the burner head by conduction and radiation is conducted into the interior of the burner. By this means the mixture of air and gas before entering the flame is better heated and the temperature of the flame, consequently the lighting effect of the burner, will be increased.

One form of construction of the new arrangement is shown in the accompanying drawings.

Figure 1 represents the burner crown of an ordinary incandescent gas burner to which are applied the parts shown in Figs. 2 and 3. Figs. 2 and 3 show ordinary fit-

tings of this class of burner. Fig. 4 shows a part to be slipped into the Bunsen tube of a burner to be converted. Figs. 5 and 6 show a complete burner fitted up according to this invention, in section and in plan respectively.

The tube *a* of the burner crown of a standard upright incandescent gas burner, shown in Fig. 1, contains the fittings Fig. 2 consisting of a gauze *b*, a conical piece *c*, and the retaining parts required therefor. These fittings Fig. 2 are secured by the top ring Fig. 3.

In order to transform the standard burner into a "Bijou" or "Gem" burner the parts shown in Figs. 2 and 3 are removed, and instead of these the tubular piece shown in Fig. 4 is placed into the burner tube *a* of Fig. 1. The fitting Fig. 4 in its lower part is of such width that it may be slipped into the Bunsen tube as shown in Fig. 5 and just fit it nicely. The fitting tube can be retained by any suitable means, for instance, by the cap *e*.

In Fig. 5 the complete arrangement is shown; it will be seen that the fitting tube is within the Bunsen tube so that the mixture of air and gas comes into contact therewith and the heat conducted from the burner head is advantageously transmitted to the mixture of air and gas.

In its details the construction shown in the drawings may be varied in different ways without in any way affecting the essence of the invention. Instead of the top plate having triangular slots as shown in the drawings the fitting Figs. 4 and 5 may have a differently arranged top plate. Instead of being held by the cap *e* the tube fitting may be fixed by other means.

Claims.

1. A fitting for converting the burner of an incandescent gas light into a smaller burner, consisting of a tubular part adapted to fit within the mixing tube of the larger burner, a smaller burner head carried by said tubular part, and projections on the tubular part adapted to be engaged between the cap and the top of the larger burner, substantially as described.

2. A fitting for converting the burner of

an incandescent gas light into a smaller burner, consisting of a tubular part adapted to fit within the mixing tube of the larger burner, a smaller burner head carried by 5 said tubular part a projection on the tubular part adapted to rest on the top of the mixing tube of the larger burner, and projections on the tubular part adapted to be

engaged between the cap and the top of the burner, substantially as described.

In testimony whereof I have hereunto set my hand in the presence of two witnesses.

HEINRICH SÜSSMANN.
